UNITED STATES PATENT OFFICE

150,439

DESIGN FOR AN ELECTRIC RAZOR

Peter C. Neilsen, Chicago, Ill.

Application September 26, 1946, Serial No. 133,572

Term of patent 14 years

(Cl. D22—3)

To all whom it may concern:

Be it known that I, Peter C. Neilsen, a citizen of the United States, residing at Chicago, in the county of Cook and State of Illinois, have invented a new, original, and ornamental Design for an Electric Razor, of which the following is a specification, reference being had to the accompanying drawing, forming part thereof, in which,

Fig. 1 is a plan view of an electric razor embodying my new design;

Fig. 2 is a side elevational view of the razor shown in Fig. 1;

Fig. 3 is a head end view of the razor shown in Fig. 1; and

Fig. 4 is a rear end view of the razor shown in Fig. 1.

The essential features of my design reside in the portions shown in full lines.

I claim:

The ornamental design for an electric razor, substantially as shown and described.

PETER C. NEILSEN.
